METHOD OF PRODUCING ALKALI METAL PHOSPHATES BY CONVERTING FERROPHOSPHORUS WITH ALKALI METAL SULPHATES

No Drawing. Application filed July 20, 1929, Serial No. 379,876, and in Germany July 24, 1928.

The present invention relates to a method of producing alkaline phosphates by converting ferro-phosphorus with alkali metal sulphates.

It has already been proposed to produce phosphates from phosphoric iron and alkali metal sulphates by heating ferro-phosphorus together with sodium sulphate and drawing out the obtained sodium phosphate by means of water. When working according to the equation:

15 3 molecules of sodium sulphate are needed to 2 atoms of phosphorus and, when the process is carried out on a practical scale, it is advisable to employ a surplus of 10 to 15 per cent of sodium sulphate.

20 Investigations carried out in connection with this process have shown that the maximum yield of water soluble substances will amount to 72,6 per cent of the amount which may be expected theoretically. Only by the 25 use of double the amount, i. e. six molecules, instead of 3 molecules of alkali metal sulphates (as given in the theoretical equation), is it possible to obtain about 90 per cent of the theoretical yield of water-soluble phosphates.

30 This excessive quantity of alkali metal sulphates which does not partake in the reaction and which contaminates the end product requires of course a considerable amount of fuel, work et cetera.

It is further a matter of fact, that when commercial potassium sulphate is used, the lime and magnesia contents of the same will exert a disturbing influence, and reduce the 40 yield of water-soluble potassium phosphate.

We have now found, that the conversion of ferro-phosphorus by the theoretical amount of alkali metal sulphates may be carried out when a certain percentage of a reduction 45 agent is added and the mixture is heated to a temperature at which the reaction will take place.

Suitable reaction agents are coals or carbonaceous substances, for instance tar or re- 50 magnesium compounds and, when this sul-

phate contains, as is well known, calcium and magnesium compounds and, when this sulphate is used, the addition of the reaction agent will have an additional effect, in that the disturbing effects of such calcium and magnesium compounds will be avoided.

Example.—2 kg. of commercial potassium sulphate containing 47 per cent of K_2O , 2,76 per cent of CaO and MgO are heated with 1 kg. of ferro-phosphorus and with 0,06 kg. of finely pulverized coal until sintering takes place or the mass is melted, whereupon the mass is cooled rapidly by pouring the same into water.

The yield of water-soluble potassium phosphate, which is removed from the melted mass in known manner, amounts to 95,1 per cent of the theoretically calculated quantity. In the mass described above 3,04 molecules of potassium sulphate are present for each two 65 molecules of phosphorus.

We claim:

1. A method of producing alkali metal phosphate from ferro-phosphorus, comprising heating ferro-phosphorus with an alkali metal sulphate in the presence of a carbonaceous reducing agent in the proportion of approximately one part by weight of ferro-phosphorus, approximately two parts by weight of alkali metal sulphate, and approximately .06 part by weight of such reducing agent until reaction takes place, and separating alkali metal phosphate from the resulting product.

2. A method of producing potassium phosphate from ferro-phosphorus, comprising heating ferro-phosphorus with potassium sulphate in the presence of a carbonaceous reducing agent in the proportion of approximately one part by weight of ferro-phosphorus, approximately two parts by weight of potassium sulphate, and approximately .06 part by weight of such reducing agent until reaction takes place, and separating potassium phosphate from the resulting product.

3. A method of producing sodium phosphate from ferro-phosphorus, comprising heating ferro-phosphorus with sodium sulphate in the presence of a carbonaceous re-

ducing agent in the proportion of approximately one part by weight of ferro-phosphorus, approximately two parts by weight of sodium sulphate, and approximately .06 part by weight of such reducing agent until reaction takes place, and separating sodium phosphate from the resulting product.

4. A method of producing alkali metal phosphate according to claim 1 wherein finely pulverized coal is employed as the reducing agent.

5. A method of producing potassium phosphate according to claim 2 wherein finely pulverized coal is employed as the reducing agent.

6. A method of producing sodium phosphate according to claim 3 wherein finely pulverized coal is employed as the reducing agent.

20 In testimony whereof we have hereunto set our hands.
